UNITED STATES PATENT OFFICE.

CHARLES W. PATTON, OF LOUISVILLE, KENTUCKY.

IMPROVEMENT IN CHURN POWERS AND TABLES.

Specification forming part of Letters Patent No. **222,726**, dated December 16, 1879; application filed November 1, 1879.

To all whom it may concern:

Be it known that I, CHARLES W. PATTON, of Louisville, in the county of Jefferson and State of Kentucky, have invented certain new and useful Improvements in Churn Powers and Tables; and I do hereby declare that the following is a full, clear, and exact description of the construction and operation of the same, reference being had to the annexed drawings, making a part of this specification, and to the letters and figures of reference marked thereon.

Figure 1 of the drawings is a representation of a plan of my churn, and Fig. 2 is a side-elevation view of the same, partly in section.

My present invention relates to a combined churn power and table; and it consists in certain improvements in the organization of the various parts with a view of rendering the same in a high degree effective, convenient, and especially adapted to the requirements of service, all as fully set forth and claimed.

In the drawings, A designates the table-legs, which are secured to a frame, B; and C, the table-top, which is secured upon the said frame by means of a hook and eye, D, and hooks E E, arranged substantially as shown, so that by disengaging the hook from the eye the top may be readily withdrawn from the remaining hooks E and removed from the frame upon which it has been secured. This frame is bent so as to form a segment of a circle, the ends of the same being connected by a bar or slat, e, which carries the mechanism for actuating the churn-dasher.

The table-top is recessed, as at c, so as to afford a space between itself and the frame for the crank-wheel which actuates the dasher-shaft, this arrangement being employed so as to bring the churn under the table, and hence out of the way.

Upon the removable table-top is secured a standard, F, which is provided with guides G for the reciprocating dasher-shaft H. This dasher-shaft is provided at its lower end with a dasher, I, which is composed of vane-shaped pieces i, formed with pins adapted to be secured

into holes in the shaft, the said vanes being set at angles, as shown.

K designates the balance and crank wheel for operating the dasher-shaft, and L a detachable pitman, which connects the two together, the said pitman being fitted at one end into one of a series of holes formed in the dasher-shaft, and at its remaining end into one of a series of holes formed in a spoke of the crank-wheel. The axis of this wheel is journaled in a casing, M, secured upon the bar e, and is provided with a gear-wheel, N, which engages with the driving-gear wheel O. This driving-wheel is formed with suitable gear-teeth for such purpose, and provided with a crank-handle, P, for operating the same.

As herein shown, the churn Q, which I have designated by dotted lines, will, when placed in position for use, be under the table and out of the way. By partially removing the table-top from its supporting-frame, the pitman can be readily disengaged from the dasher-shaft, or from both the shaft and the wheel, and then, by raising the table-top, the shaft may be entirely freed from the guides of standard F. After this the churn can be readily taken out from under the table, and either emptied or filled, as the case may be, and then the several parts reconnected for purposes of churning.

What I claim is—

In a combined table and churn-power, the table formed with a detachable top, and a standard which is arranged upon said top and provided with guides for the dasher-shaft, in combination with the dasher, operating mechanism, and a churn arranged between the table-legs in position for churning, substantially as set forth.

In testimony that I claim the above I have hereunto subscribed my name in the presence of two witnesses.

CHARLES W. PATTON.
